UNITED STATES PATENT OFFICE.

AUGUST P. JURGENSEN, OF NEW YORK, N. Y., ASSIGNOR TO CHAYES DENTAL INSTRUMENT CORPORATION, OF NEW YORK, N. Y., A CORPORATION OF DELAWARE.

REMOVABLE DENTAL BRIDGEWORK.

Application filed February 8, 1926. Serial No. 86,803.

This invention relates to improvements in removable dental bridgework.

One of the objects of the invention is to provide a method of constructing a removable bridge so that the metallic parts thereof, including the attaching portions whereby the bridge is secured to the piers, may be cast in one piece.

Another feature of the invention includes an improved friction or wear member for the attaching portions which is readily adjustable and replaceable, and simple and cheap to make.

Other objects and aims of the invention, more or less broad than those stated above, together with the advantages inherent, will appear from the following description of elements, combinations, and relations, of parts, and applications of principles constituting the invention; and the scope of protection contemplated will appear from the claims.

In the accompanying drawing, in which I have illustrated an embodiment of the invention as at present preferred:—

Fig. 1 is a plan view illustrating a bridge including my invention as it appears in use.

Fig. 2 is a perspective view of the bridge shown in Fig. 1.

Fig. 3 is a perspective view of one of the pier tooth inlays, slightly modified from the form thereof shown in Figure 1.

Fig. 4 is a sectional view with parts in elevation, illustrating the separable wear piece in its relation to the attaching portion of the bridge.

Fig. 5 is a more or less diagrammatic view showing in dotted lines a bit of straight wire on which the wear piece may be made, and showing in full lines how the same is bent so that it may be utilized for the purposes of my invention.

Fig. 6 is a perspective view showing how the wear piece of Figs. 4 and 5 is applied to such an attaching portion, as is illustrated in Fig. 1.

Fig. 7 shows the use of the new wear piece with an ordinary T-head attaching portion.

Referring to the numerals on the drawings, I have illustrated in Fig. 1 pier teeth indicated by the numeral 8 and the gap between these pier teeth is to be filled by the bridge shown in Fig. 2, this comprising a saddle 9, carrying artificial teeth 10, and provided with attaching portions 11. The pier teeth may carry inlays 12 such as shown

in Fig. 3, each of these inlays providing a seat or socket 14, these seats or sockets receiving the attaching portions 11 of the bridge. This general construction is familiar in the art and is illustrated in the Chayes Patent No. 1,366,058.

In following the construction of that patent, however, the practice has been to make a separate T-head attachment, of the kind shown in Fig. 7 of the present drawings, 65 having a shank 15. This shank 15 was soldered to the previously cast bridge, and the socket in the pier tooth was in the form of a closed bottom box around which the pier tooth inlay was cast. This box had, on its edentate side, a slot to accommodate the shank 15, and the technique involved in properly correlating and uniting the parts demanded skill and care on the part of the operator. And because the shank of the T-head was 70 merely soldered to the bridge, there were 75 important structural weaknesses.

One of the improvements constituting my invention is in the fact that the pier tooth inlay is provided with a socket which is 80 open not only at the top but also substantially wide open on the edentate side; as in Fig. 1, or slightly undercut, as in Fig. 3, and, correspondingly, the attaching portion of the bridge which fits this pier tooth socket, 85 needs no shank. Accordingly, the bridge with its attaching portion may be cast in one piece, constituting an integral, homogeneous piece of metal.

In order that the bridge, when in position, 90 may be held with desirable friction against the inner side walls of the respective pier tooth sockets, I provide a novel wear piece which is easily manufactured and readily adjustable and replaceable.

Referring to Figs. 4 to 7, inclusive, I show in the face of each attaching portion 11 of the bridge, sockets 16 which converge towards the face of the attaching portion and which communicate with a groove 17 sunk in the face of the attaching portion. 18 indicates a bit of spring wire whose ends are inserted in the sockets 16 and whose body portion will project more or less out of the groove 17, the extent of its projection determining how tightly the attachment will be held in the socket 14. Regulation is of course easily accomplished by bending the body portion of the wire more or less. This wire may be initially straight, as indicated 100 105 110

in dotted lines in Fig. 5, may then be bent somewhat, as indicated in full lines in Fig. 5, and then put in position, as indicated in Fig. 4. After the bridge has been taken 5 out of the mouth and replaced a number of times, the wire will of course lose its springiness, but this may be restored by bending the wire again, or a new one may be put in place of it.

10 It will be evident that this particular wear piece may also be utilized in connection with the form of T-head shown in the Chayes patent above mentioned, as illustrated in Fig. 7. In that case, instead of 15 sockets 16 I may make perforations 19 which extend from front to back of the T-head.

Inasmuch as many changes could be made 20 in the above construction, and many apparently widely different embodiments of my invention could be made without departing 25 from the scope thereof, it is intended that all matter contained in the above description or shown in the accompanying drawings shall be interpreted as illustrative and not 25 in a limiting sense.

It is also to be understood that the language used in the following claims is intended to cover all the generic and specific 30 features of the invention herein described and all statements of the scope of the invention which, as a matter of language, might be said to fall therebetween.

I claim:

1. A denture comprising pier teeth pro-

vided with sockets, a bridge having attaching portions fitting the sockets, sockets in each attaching portion of the bridge converging towards the outer face of the attaching portion, and a wire having its ends seated in the sockets of an attaching portion 40 and having its body portion projecting beyond the face thereof. 35

2. A denture comprising pier teeth provided with sockets, a bridge having attaching portions fitting the sockets, sockets in each attaching portion of the bridge converging towards the outer face of the attaching portion, and a wire having its ends seated in the sockets of an attaching portion 45 and having its body portion projecting beyond the face thereof, the attaching portion having a groove in the face thereof connecting the sockets and in which the body portion of the wire is seated. 50

3. A denture comprising pier teeth provided with sockets, a bridge having attaching portions fitting the sockets, sockets in each attaching portion of the bridge, and a wire having its ends seated in the sockets of an attaching portion and having its body portion projecting 55 beyond the face thereof, the attaching portion having a groove in the face thereof connecting the sockets and in which the body portion of the wire is seated. 60

In testimony whereof I affix my signature.

AUGUST P. JURGENSEN.
